RALPH K. MASON, OF BANTAM, CONNECTICUT, ASSIGNOR OF ONE-HALF TO JOHN H. LANCASTER, OF LITCHFIELD, CONNECTICUT.

SWITCH CASING AND COVER LOCK.

1,424,579.

Specification of Letters Patent. Patented Aug. 1, 1922.

Application filed June 2, 1920. Serial No. 386,126.

To all whom it may concern:

Be it known that I, RALPH K. MASON, a citizen of the United States, residing at Bantam, in the county of Litchfield and 5 State of Connecticut, have invented certain new and useful Improvements in Switch Casings and Cover Locks; and I do declare the following to be a full, clear, and exact 10 description of the invention, such as will enable others skilled in the art to which it appertains to make and use the same.

My invention relates to improvements in electric switches and more particularly to those of the enclosed safety type.

15 In the construction of buildings, particularly poured cement structures, in which there is much confusion and dirt and in which it is necessary to install the electrical conduits and outlet boxes at the time the 20 walls are poured, the usual forms of switches are subject to injury and damage if completely installed before the greater part of the building is completed, and the trade today lacks an enclosed safety switch 25 in which a part of the casing can be installed when erecting the building, while permitting the installation of the other switch parts and casing parts when the building is substantially completed and 30 roofed.

My invention aims to overcome this difficulty by the provision of a switch comprising a rear casing section carrying fixed contacts and binding posts and adapted to be 35 installed in a wall or the like when the latter is constructed, and a front casing section carrying fusible switch means and a door for giving access thereto for re-fusing, said front casing section, switch 40 means and door being applicable bodily to the rear section at any time after the latter is installed. The rear sections of the several switches necessary, which sections communicate with the usual conduits, may thus 45 be set in the wall substantially flush therewith, but it is not necessary to apply the remaining switch structure until the conditions are such that there is no danger of injury thereto, and when the latter parts

are to be applied, this may be rapidly and 50 easily done since all working parts are mounted within the front sections of the switch casings.

Another object is to so form the connecting means between the front and rear casing sections, as to permit the latter to be installed either end up, this being of great 55 advantage since unskilled laborers inserting the casing sections while erecting the walls, need not take care to install them 60 in one position only. Regardless of the position in which the rear casing section is mounted in the wall, the front section is 65 applicable thereto in the position at which it is intended to operate, and the arrangement of switch parts and contacts is such 70 that they will cooperate with the rear casing section in either position.

A further object of the invention is to 75 provide for detachably connecting the front and rear casing sections and to make novel provision for positively preventing detachment of the front section and the switch parts carried thereby, until such switch 80 parts are entirely freed from the fixed contacts of the rear casing section. It is thus impossible to slowly separate the movable contacts from the fixed contacts and consequently no injurious and dangerous arcing 85 can occur. In this connection, another aim 90 of the invention is to control the connecting means of the two casing sections by a door which is employed for giving access to interior switch parts for re-fusing, and in the preferred form of construction, interlocking means are provided between the moving 95 switch parts and the door, preventing opening of such door until the switch is entirely opened.

Yet another object is to provide a switch 90 in which part of the connecting means for the casing sections acts also as means for positively locking the door against being pried open.

A still further object is to provide a construction and arrangement of parts in which the door above referred to not only controls the means for locking the casing sec-

tions together, but serves also to prevent closing of the switch while said door stands in open position.

With the foregoing and other minor objects in view, the invention resides in the construction and combinations hereinafter described and claimed, the descriptive matter being supplemented by the accompanying drawings which illustrate the switch as now manufactured, although it is to be understood that the disclosure is for illustrative purposes only and that the inventive features claimed may be embodied in other forms.

Figure 1 of the drawings is a front elevation of an enclosed safety switch constructed in accordance with my invention.

Fig. 2 is a side elevation of the switch showing the rear section thereof inset in a wall.

Fig. 3 is a view similar to Fig. 2 but illustrating the door in open position, which is necessary before the casing sections can be either separated or connected with each other.

Fig. 4 is a vertical sectional view on the plane of line 4-4 of Fig. 3 showing more particularly the pivoted latch arm used for positively locking the two casing sections together and for locking the door closed.

Fig. 5 is a side elevation with parts in section on the plane of line 5-5 of Fig. 1.

Fig. 6 is a vertical section taken substantially on the line 6-6 of Fig. 1, showing all parts assembled for use, the switch being closed and consequently the door and the connecting means of the casing sections, being held against release.

Fig. 7 is a view similar to Fig. 6 but cut substantially on the irregular line 7-7 of Fig. 4, illustrating the switch in open position, in which position the door may be opened and the connecting means of the casing sections released.

Fig. 8 is a duplicate of Fig. 7 with the exception that it shows the door opened and the two sections of the casing in juxtaposition.

Figs. 9, 10 and 11 are horizontal sectional views cut on the planes designated by the lines 9-9, 10-10 and 11-11 of Fig. 6.

Fig. 12 is a sectional view cut horizontally on substantially the line 12-12 of Fig. 8, showing the casing sections detached and the connecting means thereof released.

Figs. 13 and 14 are perspective views showing more particularly parts of the connecting means between said sections, which means are engageable when the rear section is turned to either of two positions.

Fig. 15 is a detail perspective view of a portion of the front casing section disclosing principally the slot through which the latch arm for the casing sections extends.

In the drawings above briefly described,

the numeral 1 designates the rear section of the casing, while 2 has reference to the front section carrying all moving switch parts. The section 1 is open at its front side but is closed on all other sides and is provided at 70 suitable points with stamped portions 3 adapted to be broken out for attaching the wire conduits 4 at the most convenient locations. As shown for instance in Fig. 2, the section 1 of the casing may be set in a 75 wall 5, substantially flush with the latter, while the conduits 4 may be completely embedded in said wall.

The upper and lower ends or other opposite sides of the casing section 1 are provided with inwardly extending pins 6, two of these pins being disposed at one end and two at the other in the same spaced relation, making both ends of the casing practically identical so that it may be installed in either 80 of two positions and will not necessitate that only one specified side be disposed in a certain direction. Fixed contacts 7 are mounted in the casing section 1 and are so located that regardless of the position in which the latter 85 is installed, they will properly coat with the movable contacts 8 mounted within the front casing section 2. A one-piece base 9 is by preference employed for securely mounting the contacts 7 in the casing section 1, but obviously other constructions 90 might be used.

The front section 2 of the casing is, in the present showing, receivable within the front portion of the rear section 1, one end of 100 said section 2 having a pair of spaced openings 10 to receive either pair of the pins 6, while the other end of said section is provided with similarly spaced notches 11 to receive the other pair. By angling the two 105 casing sections, the one set of pins may be inserted into the openings 10, while complete movement of said sections into proper relation will position the other pins in the notches 11. I prefer to employ the pins 6, openings 10 and notches 11, but in some forms of construction, other details might be used. In all instances, however, I prefer that opposite sides of one casing section shall be provided with substantially identical fastening means, 115 that one side of the other casing section shall be shaped to engage either of said fastening means, and that the other side of said other section shall be engageable with the remaining fastening means. I prefer that connection 120 of the two casing sections be effected by first angling the two and then forcing them into proper relation, since it is then only necessary to lock said sections against angling, in order to securely hold them together. 125

The means for locking the casing sections 1 and 2 in operative position, may assume any adequate form, but I prefer that such locking means shall be cooperative with the door 12 of the section 2, to such an extent 130

as to be held positively against release until said door is opened. In most instances, I provide means for locking the door 12 closed until the switch is entirely free from the contacts 7 and it will thus be seen that since said door must be opened to release the section locking means of the casing and such door cannot be opened until the switch is opened, the two casing sections 1 and 2 cannot be detached without first opening the switch. Consequently there is no danger of any arcing occurring when detaching the front casing section from the rear, for instance if it is necessary to make repairs.

18 As a preferred form of the means for locking the two sections 1 and 2 together, I have shown a latch arm 13 pivoted between its ends at 14 to one side of the section 2, said arm being formed at its rear end for locking engagement with the rear casing section 1 in any preferred manner, but preferably by having a hook 15 to take over one of the pins 6 and hold such pin within its respective notch 11. The outer end of the latch lever 13 extends through a slot 16 in the front wall 17 of the casing section 2, and the door 12 which normally covers said wall 17, is provided with any suitable means, such as a slot 18, for engaging said end of the arm and holding it against movement until the door is opened.

I prefer that the front end of the latch arm 13 shall be provided with a detent 19 to engage the door 12 and latch the latter against any opening movement whatsoever, and that said arm be formed with an opening 20 to receive a padlock, thereby permitting the door to be positively locked against being pried open and injuring the internal switch parts with which it is interlocked. If desired, a suitable seal may be used instead of a padlock, such seal being passed through an opening 21 in the latch arm.

In order to hold the latch arm 13 against accidental release when the door 12 is opened, I preferably provide one side of its guiding slot 16 with a shoulder 22 which is shown most clearly in Figs. 4 and 15. As shown in Fig. 4, the arm 13 cannot move to released position until it is first sprung clear of the shoulder 22. I may also if desired, provide means for positively holding the latch arm 16 against release by unauthorized persons, and I have shown such means in the form of a screw 23 (see Figs. 4, 6 and 11) threaded through the side of the casing section 2 to which said arm is pivoted. When this screw is threaded through the casing sufficiently, it is in the path of the arm 13 and consequently the latter cannot be released, and an appropriate seal may be used for holding the screw against being turned to an inactive position. I have shown an opening 24 through the head of the screw 23 adjacent an apertured lug 25

on the casing section 2, for the purpose of receiving a seal of ordinary form. When the screw 23 is threaded far enough into the casing a padlock may be inserted in the large opening in lug 25 so that it will stand in the way of the removal of the screw 23 and hence a more secure fastener will be provided than a mere seal.

The door 12 is preferably mounted on hinges 26 and these hinges are secured to the casing section 2, so that said section and door are applicable to and removable from the rear casing section 1, as a single unit which also comprises the movable switch parts. These parts may of course vary but they are preferably of substantially the form shown in my pending United States application Serial No. 309,280, filed July 8th, 1919. The contacts or switch blades 8 are carried by a movable base 27 which is mounted on parallel linkage including two links 28 and two similar links 29, the latter serving also as crank arms for operating the switch. The links 28 are pivoted at one end to the base 27 and at their other ends to the casing section 2, and the arms 29 are pivoted at one end to said base while their other ends are fixedly mounted on a rock shaft 30 having an operating handle 31 on the exterior of the casing. One of the arms 28 carries a flat sided lug or the like 32 operable in a keyhole slot 33 which is formed in a door-locking link 34, such link being pivoted to the door 12, at 35. This locking mechanism is also disclosed in the application above referred to and hence it will suffice to state that when the switch is in closed position it locks the door against opening, when the switch is opened, it permits opening of the door, and while said door stands opened, it prevents closing of the switch. Since the door in question controls the opening of the casing lock 13, the switch-controlled locking means for the door also controls said means 13 indirectly, preventing release thereof when the switch is closed.

In the present application, I have shown a switch of quick-break nature, in which the moving switch parts are held in closed position against the tension of a spring 36 acting on any of the switch moving parts, in the present instance upon one of the arms 29. A spring latch 37 serves to hold the switch closed against the action of the spring 36 and it will thus be seen that when said latch is released, the spring will rapidly move the base 27 to switch-open position. The latch 37 preferably acts on a shoulder 38 on a disc 39 carried by the rock shaft 30 as seen in Fig. 6, and this disc is provided with circumferentially spaced shoulders 40 between which a pin 41 on the handle 31 is movable, said pin 41 passing through a slot 42 in the front casing section 2 and coact-

ing with the shoulders 40 of the disc 39 to provide for lost motion between the handle 31 and the shaft 30, said handle being loosely mounted on said shaft in any preferred manner.

This lost motion is of use in permitting the handle 31 to be moved substantially from switch-closed to switch-open position and then releasing the latch 37 by means of 10 said handle, for which purpose the handle is provided with an appropriate cam 43.

The construction just briefly described for closing the switch against spring tension and quickly opening the same under 15 the action of the spring, is protected by my United States application, Serial No. 386,125, filed June 2, 1920, and hence need not be amplified in the present case. Similarly the movable contacts 8 are mounted on 20 the base 27 and connected by fuses 44, in a manner forming no part of the present application but disclosed fully in Serial No. 309,280, above referred to.

The general operation of the switch is as 25 follows, assuming that the switch parts are in circuit-making position as shown in Fig. 6. With the parts in this position, the lug 32 and the link 34 lock the door 12 against opening and said door locks the latch lever 30 13, with the result that the latter securely locks the two casing sections 1 and 2 together, and if a padlock be passed through the opening 20, said lock will prevent any 35 possibility of the casing door being pried outwardly, so that no injury will be inflicted on the internal switch parts. Furthermore, it will be seen that should the latch mechanism 34-32 be omitted, the padlock will lock the door against opening and consequently 40 the latter will hold the latch 13 in inactive position. I prefer however to employ the parts 32 and 34 in all instances. When the switch is to be opened, the handle 31 is moved toward the word "OFF" appearing 45 on the door 12 or at any other suitable place. The handle idles throughout the greater part of this movement but toward the end of such movement, the cam 43 strikes and releases the latch 37 as will be 50 clear from Figs. 2 and 3. The spring 36 then immediately comes into play to open the switch, at the same time projecting the fuses 44 through an opening 45 in the front wall 17 of the casing section 2. The movable base 27 is at the same time moved forwardly to cover the opening 45, preventing any access to interior parts when the door 12 is opened. Opening of this door may now be effected since the lug 32 then stands longitudinally of the slot 33 as seen in Fig. 7. Before the door can be opened however it is necessary to remove the seal or lock from the latch arm 13 and spring the latter to free the detent 19. When the door is now 60 65 opened to the position of Figs. 3 and 8, the

fuses 44 are accessible for renewing and the latch arm 13 is held against accidental release by the shoulder 22, even though the locking screw 23 is not used. If it is now desired to detach the front casing section, 70 the latch arm may be moved by hand from the locking position shown in Figs. 10 and 11 to the released position of Fig. 12, whereupon the casing section 2 may be angled to first withdraw the notches 11 from their respective pins 6 and to then disengage the other pins 6 from the openings 10. The switch being now entirely opened, there is no danger of arcing such as would occur if the movable contacts 8 were permitted to 80 be moved slowly away from the fixed contacts 7, while separating the two casing sections.

After opening the door 12 at any time, the base 27 and its operating means cannot move 85 to close the switch until the door is closed, due to the relation of the lug 32 and slot 33, depicted in Fig. 8. As soon as the door is closed however the switch may be closed and when this takes place the door is automatically locked against opening. Attention may here be directed to the fact that since the latch arm 13 must project through the slot 18, door 12 cannot be closed with 90 said latch arm in an inactive position.

I attach great importance to the following: The rear casing section 1 may be installed when the building is erected; the front casing section 2 permanently carries the re-fusing door 12 and the fusible switch means and is engageable with said rear section 1, whether the latter be turned to either of the positions at which it may be installed; the casing sections cannot be separated while the switch is closed; the switch-controlled locking mechanism for the door 12 indirectly locks the means 13 for locking the two casing sections together; the latch arm 13 cannot be accidentally released when the door 12 stands opened; and said door cannot be closed when said latch arm is in any but effective position. The switch is truly a safety switch and in addition to possessing this and the several other advantages above pointed out after installation, it is of great advantage to the contractor and may be manufactured and marketed to great advantage.

While in the foregoing and in the claims I have used the terms such as "fuse" and "fusible switch means," I wish it understood that any equivalent of a fuse may be substituted, since it is obvious that the circuit may be automatically interrupted or broken at any predetermined amperage or load by 110 any suitable means.

Since excellent results have been obtained when manufacturing the switch in accordance with the present disclosure, the several features of novelty preferably assume the 115 120 125 130 135

forms herein referred to, but within the scope of the invention as claimed, they may well be embodied in numerous other forms, and in all instances, it is not necessary that 5 the novel casing structure be limited to use in connection with switches, although this is the principal intent.

I claim:

1. In a switch, a rear casing section carrying contacts, fusible switch means and a door giving access thereto for re-fusing, a front casing section carrying both said switch means and said door and forming therewith an integral unit applicable bodily 15 to said rear section, and means for securing said front and rear sections together.

2. In a switch, a rear casing section carrying a pair of contacts, a movable base carrying a pair of contacts for separable engagement with said first named contacts, a fuse between said base-carried contacts, a door for giving access to the fuse, a front casing section in which said base is mounted and by which said door is carried, said front section, said base and said door forming a single integral unit applicable bodily to said rear section, and means for securing said casing sections together.

3. In a switch, a rear casing section carrying contacts, fusible switch means and a door giving access thereto for re-fusing, a front casing section equipped with said switch means and door and forming therewith a single integral unit applicable bodily 30 to said rear section, and means under the control of said door for securing said casing sections together.

4. In a switch, a rear casing section carrying contacts, a front casing section equipped with fusible switch means cooperable with said contacts, means for locking said sections together, means for locking the switch in open position while re-fusing, and a multi-function door for permitting re-fusing, for applying said switch locking means when the door is opened, and for locking said section locking means against release when said door is closed.

5. In a switch, front and rear casing sections engageable when turned to either of two positions, separable switch units carried by said casing sections respectively and engageable when said sections are assembled in either of said positions, and connecting 55 means for said sections operable in either of said positions.

6. In a switch, front and rear casing sections engageable when turned to either of two positions, separable switch units carried 60 by said casing sections respectively and engageable when said sections are assembled in either of said positions, and locking means at one side of one casing section engageable with either side of the other section.

65 7. In a switch, front and rear casing sec-

tions engageable when turned to either of two positions, separable switch units carried by said casing sections respectively and engageable when said sections are assembled in either of said positions, means controlled 70 by relative movement of the casing sections for securing either side of one section to one side of the other section, and means for locking other sides of said sections together.

8. In a switch, front and rear casing sections engageable when turned to either of two positions, separable switch units carried by said casing sections respectively and engageable when said sections are assembled in either of said positions, one of said sections having similar projections at opposite sides and the corresponding sides of the other section having an opening and a notch respectively to receive said projections when the sections are assembled in either position, 80 and means for locking the notch-received projection in the notch.

9. In a switch, a rear casing section carrying contacts, a front casing section carrying fusible switch means and a door for giving access thereto for re-fusing, and means for locking the two casing sections together, said locking means having means engaging said door for normally holding the latter closed and for preventing release 95 of said locking means until said door is opened.

10. In a switch, a rear casing section carrying contacts, a front casing section carrying fusible switch means and a door for giving access thereto for re-fusing, and a latch arm pivoted to said front section and engaging said rear section to lock the two together, said door having means to engage said arm and hold it against release 100 until the door is closed.

11. In a switch, a rear casing section carrying contacts, a front casing section carrying fusible switch means and a door for giving access thereto for re-fusing, and a latch arm pivoted to said front section and engaging said rear section to lock the two together, said door having a slot through which one end of said arm projects to hold such arm against release when the door is 115 closed, said projecting arm end carrying means for normally holding said door closed.

12. In a switch, a rear casing section carrying contacts, a front casing section carrying fusible switch means and a door for giving access thereto for re-fusing, and means carried by said front casing section for locking it to the rear section, said door having means for holding said locking means against release until such door is 120 opened, and said front section having means to prevent accidental release of said locking means when the door is opened.

13. In a switch, a rear casing section carrying contacts, a front casing section

carrying fusible switch means and a door for giving access thereto for re-fusing, a latch arm pivoted to said front section for securing it to the rear section, said front section having a slot through which said arm projects, said slot having a shoulder to hold said arm against accidental release when the door stands open, said door having means to engage said arm and hold it against release until the door is opened.

14. In a switch, a rear casing section carrying contacts, a front casing section carrying switch means, means for detachably connecting the two sections, and means positively preventing detachment of said sections until the switch means is entirely freed from the contacts.

15. In a switch, a rear casing section carrying contacts, a front casing section

carrying fusible switch means and a door for giving access thereto for re-fusing, door controlled means for locking the two casing sections together until the door is opened, and means for locking said door closed until the switch is opened.

16. In an enclosed switch, a sectional switch-containing casing having a door, and door controlled means for locking the casing sections together until the door is opened.

17. In an enclosed switch, a sectional switch-containing casing having a door, switch controlled means for locking said door, and door-controlled means for locking the casing sections together.

In testimony whereof I have hereunto set my hand.

RALPH K. MASON.
